(57) **CLAIM**

The ornamental design for a fixing plate, as shown and
described.

DESCRIPTION

FIG. 1 is a perspective view of the fixing plate showing my
new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a sectional view thereof taken from line 8-8 in FIG.
2, illustrating that the rear end thereof is inclined from a
vertical reference line.

The broken lines are for illustrating environment structure
only and form no part of the claimed design.

1 Claim, 7 Drawing Sheets
